(57) **CLAIM**

The ornamental design for a lighting device as shown and described.

DESCRIPTION

FIG. 1 is a top front perspective view of a lighting device according to the present design.

FIG. 2 is a bottom rear perspective view of the lighting device of FIG. 1.

FIG. 3 is a front view of the lighting device of FIG. 1.

FIG. 4 is a back view of the lighting device of FIG. 1.

FIG. 5 is a left side view of the lighting device of FIG. 1.

FIG. 6 is a right side view of the lighting device of FIG. 1.

FIG. 7 is a top view of the lighting device of FIG. 1; and,

FIG. 8 is a bottom view of the lighting device of FIG. 1.

The broken lines in the drawings depict portions of the lighting device that form no part of the claimed design.
